CLAIM

The ornamental design for sound activated light switch, as shown and described.

DESCRIPTION

FIG. 1 is a top, front and left side perspective view of a sound activated light switch showing my new design; FIG. 2 is a top plan view thereof; FIG. 3 is a right side elevational view thereof; FIG. 4 is a bottom plan view thereof; FIG. 5 is a left side elevational view thereof; FIG. 6 is a rear elevational view thereof; and FIG. 7 is a top, front and left side perspective view of a second embodiment wherein the only difference resides in the inclusion of the toggle switch.
